UNITED STATES PATENT OFFICE

137,332

DESIGN FOR A COMBINATION CIGARETTE CASE AND ASH TRAY

Nellie R. Fleischer, Pittsburgh, Pa.

Application August 26, 1943, Serial No. 111,001

Term of patent 14 years

To all whom it may concern:

Be it known that I, Nellie R. Fleischer, a citizen of the United States and residing at Pittsburgh, in the county of Allegheny and State of Pennsylvania, U. S. A., have invented a new, original, and ornamental Design for a Combination Cigarette Case and Ash Tray, of which the following is a specification, reference being had to the accompanying drawing, forming a part thereof, wherein the figure is a perspective view of a combination cigarette case and ash tray embodying my new design.

The end, side, and back which are not shown in this figure are plain.

I claim:

The ornamental design for a combination cigarette case and ash tray, substantially as shown and described.

NELLIE R. FLEISCHER.
